A. L. TOLMAN & F. L. TAYLOR.
DEVICE FOR MAKING DESIGNS.
APPLICATION FILED JULY 15, 1908.

914,322.

Patented Mar. 2, 1909.

UNITED STATES PATENT OFFICE.

ABRAHAM L. TOLMAN AND FRANK L. TAYLOR, OF ORANGE, MASSACHUSETTS, ASSIGNORS
TO NOVEL IDEA COMPANY, OF ORANGE, MASSACHUSETTS.

DEVICE FOR MAKING DESIGNS.

No. 914,322.

Specification of Letters Patent.

Patented March 2, 1909.

Application filed July 15, 1908. Serial No. 443,734.

To all whom it may concern:

Be it known that we, ABRAHAM L. TOLMAN and FRANK L. TAYLOR, citizens of the United States, residing at Orange, in the 5 county of Franklin, State of Massachusetts, have invented a new and useful Device for Making Designs, of which the following is a specification.

This invention relates to machines of that 10 class employed for making fanciful scroll designs, and operates generally on the principle of a geometrical lathe, the pencil, pen, or stylus being so mounted and operated as to trace various designs on paper, slate, or 15 other surface.

The principal object of the invention is to provide a machine of very simple and economic construction which may be readily operated by a child, and which may be also 20 employed by engravers or others in the production of fanciful scroll work.

A still further object of the invention is to provide a machine in which all of the mountings may be readily adjusted for the purpose 25 of changing the character of the design produced, and further to so arrange and construct the operating mechanism that the support for the paper or other surface may be revolved at different speeds and in different directions.

With these and other objects in view, as will more fully hereinafter appear, the invention consists in certain novel features of construction and arrangement of parts, herein- 35 after fully described, illustrated in the accompanying drawings, and particularly pointed out in the appended claims, it being understood that various changes in the form, proportions, size and minor details of the 40 structure may be made without departing from the spirit or sacrificing any of the advantages of the invention.

In the accompanying drawings:—Figure 1 is a perspective view of a machine for making 45 designs constructed in accordance with the invention. Fig. 2 is a side elevation of the device, parts being broken away in order to more clearly illustrate the same. Fig. 3 is a detail perspective view of the pencil or 50 stylus carrier showing the various parts detached. Fig. 4 is a detail view of the holding clamp for the pencil carrier. Fig. 5 is a detail section through the crank pin and its connections.

Similar numerals of reference are em- 55 ployed to indicate corresponding parts throughout the several figures of the drawings.

The working parts of the machine are supported by a suitable frame, which in the 60 present instance comprises a pair of wooden or metallic strips 10 and 11 which are connected by a table or platform 12.

The table 12 is provided with bar openings 65 for the reception of a pair of vertical shafts 15 and 16. To the upper end of the shaft 15 is secured a crank disk 17, the periphery of which is grooved to form a driving pulley, and to the lower end of the shaft 15 is secured a smaller driving pulley 18. To the upper 70 end of the shaft 16 is secured a disk 20 that is provided with a grooved periphery which may be made to receive a belt so that it may be driven from the disk 17, and the belt may be crossed or straight in order to revolve the 75 disk 20 in either direction. To the lower end of the shaft 16 is secured a grooved pulley 21 which is shown as connected to the small pulley 18 by a cross belt 22 so that movement is imparted from the shaft 15 to the shaft 16 at 80 a comparatively low rate of speed.

Extending diametrically across the top of the disk 17 is a pair of spaced guiding strips 24 which serve for the reception of a slidably adjustable bar or plate 25 to which is secured 85 the lower end of a crank pin 26. The upper end of the crank pin is turned outward to form an operating handle that is provided at its outer end with a small revoluble knob 27. The lower portion of the crank pin 26 is 90 threaded and receives a clamping nut 29, which when turned down engages against the top of the guides 24 and locks the plate 25 in place; by loosening the nut the plate may be freely shifted within the guides in order to 95 adjust the distance of the crank pin from the axis of rotation of the disk.

Mounted on the threaded portion of the crank pin is a nut 30 which forms a stop for limiting the downward movement of a collar 100 31 that is guided on the pin, and said collar is normally depressed by a spring 32 the upper end of which bears against a fixed collar or flange 33 carried by the crank pin.

Extending from the collar 31 is a stylus or 105 pencil supporting arm 35. This arm is formed of two sections, one of which is preferably made of sheet metal and bent into the

form of a sleeve for the reception of a rod 36, the outer end of which is turned to form an eye 37 that fits over a vertical pin 38 carried by an adjustable slide 39. The slide 39 is made of sheet metal, and its opposite sides are inwardly crimped to engage the grooves that are formed on the opposite sides of the upper portion of the bar 11. The slide is preferably made of metal of a more or less elastic nature so that it will hug closely to the side of the bar 11 and retain its position without the necessity of employing any auxiliary securing devices. Surrounding the pin 38 is a helical compression spring 40 that tends to force the rod 36 downward.

Mounted on the section 35 of the connecting bar is a slide 42 from which projects a clip 43 adapted to carry a pencil, pen, stylus, or other marking device. The stylus carrier is firmly clamped in position by an auxiliary spring clamp 45 that is provided with a pair of outwardly projecting wings 46 for convenience in opening it to release position so that the stylus carrier may be freely moved along its carrying rod.

The disk 20 is arranged for the reception of a marking surface such for instance as a piece of paper or slate or metal having a prepared surface to be engraved or etched.

In operation the paper or other marking surface is secured on the disk 20 and the stylus carrier is adjusted to the desired point in the length of the connecting rod 35. The position of the crank pin is then adjusted and the slide 39 is shifted to the required point. The crank pin is then revolved by grasping the knob 27. The outer end of the stylus carrying rod will swing on the pin 38 while that end connected to the crank pin will describe a circle, the radius of which is determined by the adjustment of the pin. The stylus carrier will thus be made to travel in an approximately ovate path, and as the disk 20 is revolving the line described by the stylus will be in the form of a continuous scroll.

Owing to the various adjustments the stylus may be made to travel in many distinct lines to produce scroll work of different patterns, and various geometrical figures the appearance of which may be varied by employing pencils or other marking devices of different colors.

What is claimed is:—

1. In a machine of the class described, a revolute support for the surface to be marked, a driving disk operatively connected to said support, a crank pin adjustably mounted on said disk, a two part rod, one end of which is connected to the crank pin, an adjustable support to which the opposite end of the rod is pivoted, and a

stylus carrier mounted on that portion of the rod connected to the crank pin.

2. In a machine of the class described, an operating member including an adjustable crank pin, a stylus carrier, a telescopic supporting rod for said carrier, one end of the rod being connected to the crank pin, an adjustable support for the opposite end of the rod, a revolute carrier for the surface to be marked, and means for connecting said carrier to the operating lever.

3. In a machine of the class described, a revolute crank disk, a crank pin thereon, a rod receiving motion from the crank pin, a stylus clamp on said rod and adjustable in the direction of the length of the rod, means for guiding the outer end of the rod, and a revolute carrier for the surface to be marked.

4. In a machine of the class described, a base, driving and driven shafts journaled therein, pulleys carried by the shafts, a connecting belt between the pulleys, a disk carried by the driving shaft, a pair of guiding strips extending diametrically of the disk, a slideable block mounted in said guides, a crank pin supported by the block and having a threaded lower portion, a locking nut mounted on the threaded portion of the pin and arranged to clamp against the guiding strips, a stop nut carried by the threaded portion of the pin, a movable slide, a guiding pin thereon, a telescopic rod having one end mounted on the guiding pin and the other end on the crank pin, springs arranged on both pins and tending to depress the rod, a clip slidably adjustable on the rod and arranged to receive a stylus, a clamp for holding said clip in place, and a disk carried by the driven shaft and arranged for the reception of the surface to be marked.

5. In a machine of the class described, a base plate, a pair of supporting bars therefor, driving and driven shafts journaled in the plate, disks secured to the upper and lower ends of both shafts and provided with peripheral grooves forming pulleys, a belt connecting one set of pulleys, an adjustable crank pin carried by one of the disks, a stylus carrier receiving motion from the crank pin, and means on one of the driven disks for supporting the surface to be marked.

In testimony that we claim the foregoing as our own, we have hereto affixed our signatures in the presence of two witnesses.
